Primary Examiner—Nelson C. Holtje*Assistant Examiner*—Martha Thompson*Attorney, Agent, or Firm*—Jordan and Hamburg[57] **CLAIM**

The ornamental design for a combined holder and dispenser for correction tape, as shown and described.

DESCRIPTION

FIG. 1 is a front elevational view of a combined holder and dispenser for correction tape showing our new design;

FIG. 2 is a rear elevational view thereof;

FIG. 3 is a right side elevational view thereof;

FIG. 4 is a left side elevational view thereof;

FIG. 5 is a top plan view thereof;

FIG. 6 is a bottom plan view thereof;

FIG. 7 is a bottom, right front perspective view of FIG. 1 drawn to an enlarged scale;

FIG. 8 is a top, left front perspective view of FIG. 1; FIG. 9 is a bottom, rear perspective view of FIG. 1 drawn to an enlarged scale;

FIG. 10 is a top, right front perspective view thereof drawn to a reduced scale; and,

FIG. 11 is a perspective view thereof in an exploded condition.

The fragmentary showings of the hand, paper and correction tape depicted by means of broken lines in FIG. 10 have been shown for illustrative purposes only and form no part of the claimed design.
